(57) **CLAIM**

The ornamental design for a digital audio player with tuner and amplifier for an automobile, as shown and described.

DESCRIPTION

FIG. 1 is a perspective view of a digital audio player with tuner and amplifier for an automobile showing my new design;

FIG. 2 is a front view thereof;

FIG. 3 is a top view thereof; and,

FIG. 4 is a left side view thereof.

The broken lines illustrating portions of the digital audio player with tuner and amplifier for an automobile form no part of the claimed design.

1 Claim, 4 Drawing Sheets
